SHOE

Charles E. Edwards, Beverly, Mass., assignor to
 United Shoe Machinery Corporation, Borough
 of Flemington, N. J., a corporation of New
 Jersey

Application November 11, 1937, Serial No. 174,083

7 Claims. (Cl. 36—45)

This invention relates to shoes and particularly to shoes having uppers made of fabric in whole or in part. While the invention is illustrated as embodied in a shoe made completely of fabricated material, for example, of textile and felted material, it is to be understood that various important features of the invention may have other applications and uses.

It is an object of the invention to provide a shoe which will be especially flexible and elastic so that, while it feels comfortable and yielding to the foot, it will be easy to put on and take off and will hug the foot sufficiently to prevent undue slipping of the latter in the shoe.

It is an important feature of the invention that, in a shoe upper assembly including an upper and a lining member of elastic fabricated material cut on a bias to provide elastic portions at the throat and also along the top marginal portion of the united upper and lining, a reinforcing member is provided to serve as a backing for the elastic material at all points where the shoe upper would tend to be distorted while the shoe is being worn. As illustrated, this reinforcing member is located between the upper and lining members and is cut away along its top edge so that it leaves the upper and lining free to stretch along the top edge thereof while the shoe is in use. Preferably, the reinforcing member is made of non-stretchy material and is also substantially cut away at the throat of the shoe. An elastic reinforcing member is secured to the upper and lining members in the space thus provided at the throat of the shoe. Furthermore, to insure the proper elastic effect so that the top edge portion of the shoe upper will closely hug the foot and yet yield to the flexing movements of the foot in walking, an elastic tape member is cemented or otherwise secured to the inside surface of the upper member along substantially the whole of its top edge and rests in the space between the upper and lining members above said reinforcing member. To contribute materially to the elasticity of the top edge portion of the assembled upper and lining members, the rows of stitches used as securing means along this edge are made, in part at least, with an elastic thread so that this edge portion of the assembled upper may stretch without breaking the thread used in sewing the seams.

In the making of the shoe, the lining member is first sewed to the upper by a line of stitches near the top edges of the lining member and upper while the former is in contact with the outside surface of the upper. The lining member is then

turned or folded over the top attached edges of the lining and upper members, to the inside of the upper as a preliminary to the insertion of another line of stitches through the upper member and the folded over lining member, whereby the lining will appear inside of the assembled shoe upper, thus making a finished upper edge having a French binding effect.

These and other important features of the invention will be described in detail in the specification and then pointed out more particularly in the appended claims.

In the drawings,

Fig. 1 is a plan view of an upper fabric blank for a shoe;

Fig. 2 is a plan view of a fabric reinforcement blank for the same shoe;

Fig. 3 is a plan view of a doubler;

Fig. 4 is a plan view of a lining blank;

Fig. 5 is a perspective view of the whole upper assembly, after turning but before it has been applied to a last, looking at the inside of such assembled shoe upper;

Fig. 6 is a perspective view of the assembled upper when viewed from the outside after turning, the outer layer being partly broken away;

Fig. 7 is a sectional view through an edge portion of the upper assembly before the lining has been turned and top stitched;

Fig. 8 is a sectional view along the line VIII—VIII of Fig. 6; and

Fig. 9 is a perspective view of the completed shoe.

In the illustrated embodiment of the invention, a shoe upper 10 is made of a special textile fabric, such as "Lastex," in which the warp consists of rubber threads, the fabric being cut on a bias to provide a blank, such as that shown in Fig. 1, which will stretch both transversely and longitudinally of the completed shoe. For assembly with the upper 10 there is provided a doubler 12 and a lining 14 both made of elastic fabric similar to that of the upper. There is provided also a non-elastic reinforcing member 16 which is preferably of a special fabric, such as "Tufsta," possessing to a substantial degree the qualities of toughness and flexibility. This reinforcing member 16 is cut approximately one-half inch narrower than the upper and lining blanks so as to have no portion interposed between the upper and lining where these members are united along the upper or top edge of the shoe. By this arrangement the elasticity of the upper and lining members 10 and 14 are left unobstructed along said top edge portion of the

shoe whereby said edge portion may readily yield, by stretching, during movements of the foot in walking and when the shoe is put on and taken off. Furthermore, the reinforcing member 16 is cut downwardly very considerably below the throat of the shoe opening, as indicated at 18 in Figs. 2 and 5, thus leaving the elasticity of the upper 10 and lining 14 unimpaired at the throat part of the shoe. It is preferable, however, that this part of the upper and lining should be reinforced by an elastic member 20, the central portion of which is cemented to the upper and to the lining crosswise of the throat portion of the shoe, the ends of the member 20 being cemented to the upper 10 and to the reinforce 16 which is next to the upper. It is to be understood, however, that the ends of the member 20 may be cemented in between any two of the four members 10, 16, 12, 14, 20 of the assembled shoe upper. There is preferably provided also an elastic reinforcing tape 22 (Figs. 5, 6, 7 and 8) which is cemented to the inside surface of the upper along the upper or top edge thereof in the assembled shoe, the opposite face of the tape 22 being also cemented so that, when the lining is folded over against the tape 22 as a preliminary to a top stitching operation, the lining and tape will adhere, the tape 22 being thus secured to the lining along its top margin as well as to the upper 10. As shown, the doubler 12 is provided as a part of the upper assembly, the purpose being to add weight and plumpness to the upper. When said doubler is used, it is also cut away at the throat of the shoe, as indicated at 23 in Fig. 5, to furnish a space for the elastic reinforcing member 20, the cut-away part being not so extensive as in the case of the reinforcing member 16, as will be evident upon comparison of the blanks in Figs. 2 and 3. It will be noticed, furthermore, that the blank 12 of the doubler is smaller than the upper and lining blanks 10 and 14, since the doubler is not to be secured in place by stitching to the top edges of the upper and lining. However, the blanks of the upper 10, the doubler 12, the lining 14, and the reinforce 16 have substantially the same overall dimensions, since as parts of the assembled upper they are all secured in overlaid position upon the shoe bottom. In assembling the upper, the reinforcing member 16 is cemented directly to the upper, the doubler 12 is cemented to the reinforcing member 16, and the tape 22 is cemented to the top inside margin of the upper 10. Also in the assembling operation, the lining is stitched to the upper, then turned over the top edges of the upper and of the lining and tape members (after cement has been applied to said edges) as a preliminary to again stitching the lining to the upper in top stitching, with the result that the lining is both cemented and stitched to the upper along the upper or top edge thereof, and thus provides an edge to the assembled upper that has the appearance of a French binding.

In making the illustrated shoe, the upper 10 and the lining 14 are secured together by two seams 28 and 30, as most clearly shown in Fig. 8. The first seam 28 is for the purpose of securing together the upper 10 and the lining 14 while the side of the lining which is to be next to the foot is resting on what is to become the outside surface of the upper, although said surface is at the time on the inside due to the fact that, for assembling and stitching operations, both lining 14 and upper have been closed by separate back

seams and then assembled while turned inside out. Before insertion of the stitches 28, the tape member 22 is secured to the top marginal portion of the upper 10 on what is to be the inside surface of the latter, cement being used 5 to secure the tape in place. Hence the line of stitches 28 will pass through the lining 14, the upper 10, and also the tape member 22. How cement is applied along the combined top edge portions of the lining, upper and tape member, 10 and is spread over at least a portion of the then exposed surface of the tape 22 so that, upon turning the lining outwardly, it laps over the combined edges just mentioned and is secured thereto and to the tape member by the freshly applied 15 cement. The lining is then stitched again to the upper by the line of stitches 30 (Fig. 8) passing also through the tape member 22, the operation being known as top stitching and having the result of producing an edge with a French 20 binding effect. Following this operation, the assembled upper is turned to put the lining 14 on the inside and the upper 10 on the outside where it belongs in the completed shoe.

Both seams 28 and 30 are made by using two 25 threads, an upper thread and a lower or bobbin thread. In each case, the upper thread is a non-elastic cotton thread while the lower, or bobbin thread, is an elastic thread. In both cases, the thread tensions are such that the loops of the 30 bobbin thread normally extend about one-quarter of the way through the stitched-together upper materials while the loops of the upper or non-elastic thread extend substantially three-quarters of the way through the upper materials. 35 When the upper assembly in the finished shoe is stretched lengthwise of the seams, the relatively long loops of the non-elastic thread are shortened while at the same time the relatively short loops of the elastic thread are lengthened 40 due to the stretching of that elastic thread. While the upper materials remain in a stretched condition the loops of the upper and lower threads should interlock substantially midway between the inner and outer surfaces of the 45 assembled upper materials. The seams or lines of stitches are thus so formed as to offer no resistance to the stretching of the sewed materials, whereas stitches of the ordinary types would have the effect of stiffening the material 50 and making it resistant to stretching.

Preferably the upper 10, because of its elastic quality, is cut one size smaller than usual. For example, a size nine upper will serve for a size ten shoe. In this connection, it is to be noted that the cutting of the elastic material for an upper 55 blank 10 is carried out in such a way that the elastic threads of the material are directed at a 45° angle to the long axis of the shoe at the throat portion thereof, that is, the material is cut on the bias so that such material will stretch both lengthwise and crosswise of the shoe at the throat, as well as all around the top edge. As already stated, the upper 10 is closed by a back seam separate from that of the lining back seam. 60 Furthermore, both the upper 10 and the lining 14 are cut in such a way as to remove about one-eighth of an inch on each side of the back seam for a short distance at the top of the back seam, as indicated at 32 in Figs. 1 and 4, thereby drawing in the back seam for about an eighth of an inch at the upper end thereof, as at 34 (Fig. 9), to cause the upper margin of the finished shoe to hug the heel and to minimize gapping of the upper away from the foot at each step of the 65

wearer. Preferably also the lining blank is a little shorter than the corresponding upper blank (Figs. 1 and 4) so that, when the rear edges of each part are sewed throughout their lengths in the regular manner and these parts subsequently secured in overlasted position upon the shoe bottom, the finished lining is normally a little shorter from toe to back seam than the corresponding upper, with the result that the lining in the finished shoe hugs the heel with yielding pressure to hold the shoe (in this case a pump) more securely in place on the foot. In other words, the elastic lining tends to minimize slipping of the shoe on the heel portion of the wearer's foot, and to lessen very materially friction between the shoe at the heel portion thereof and the foot of the wearer. While, as illustrated, the lining blank 14 is cut shorter than the upper blank 10, it will be understood that the blanks may be the same in length and that the line of back seam stitching through the lining may be located a little farther in from the rear edges than is the case with the upper to shorten the lining by the difference in distance of the lines of back seam stitching from the rear edges of the blanks.

Having described my invention, what I claim as new and desire to secure by Letters Patent of the United States is:

- 30 1. In a shoe, an elastic fabric upper cut on the bias to allow stretching both lengthwise and crosswise thereof, a non-elastic reinforcing member secured with said upper in overlasted position upon the shoe bottom and nearly coextensive therewith to furnish a support or backing for such upper throughout the greater portion of its area, said reinforcing member having a part cut away at the throat of the shoe to leave a space for stretching of the upper both lengthwise and crosswise of said throat, and an elastic member disposed across said space and secured to the upper to increase the elastic effect of the latter at the throat of the shoe.
- 45 2. In a shoe, an elastic fabric upper, an elastic fabric lining member united to the upper along their top edges, and a reinforcing member of non-elastic material interposed between the upper and the lining member and secured with upper and lining member in overlasted position upon the shoe bottom to furnish backing for the upper throughout the greater part of its area and so constructed and arranged as to leave a space above the level of the said reinforcing member where the top margins of the upper and lining member may be secured together with no non-elastic material interposed between them, whereby the elastic quality of the assembled upper and lining members around the top edge portions thereof causes said edge portions yieldingly to engage the foot.
- 60 3. In a shoe, an elastic fabric upper, an elastic fabric lining member united to the upper along their top edges, and a reinforcing member of non-elastic material interposed between the upper and the lining member and secured with said upper and lining member in overlasted position upon the shoe bottom to furnish backing for the upper and lining member and so constructed and arranged as to leave a space above the level of the said reinforcing member where the top margins of the upper and lining member may be secured together with no part of said reinforcing member interposed between them, said reinforcing member being also cut away substantially at the throat above the level of the toe portion
- 5 5. of the upper so that the throat portions of the upper and lining member are free to stretch under pressure of the foot, whereby the top edge portions of the assembled upper together with the throat portion thereof may yieldingly engage the foot.
- 10 4. In a shoe, an elastic fabric upper, an elastic fabric lining member united to the upper along their top edges, an elastic tape member secured to said upper along the top margin of the latter, and a reinforcing member of non-elastic material interposed between the upper and the lining members and secured with the latter to the shoe bottom to furnish backing for the upper throughout the greater part of its area and so constructed and arranged as to leave a space above the level of said reinforcing member at the top margins of the upper and lining to receive said elastic tape member, said tape member being interposed between the upper and the lining and serving to augment the elastic effect of the assembled upper around the upper edge portions of the latter.
- 15 5. In a shoe, an elastic fabric upper, an elastic fabric lining member united to the upper along their top edges, a reinforcing member of non-elastic material interposed between the upper and the lining members and secured with the said members to the shoe bottom to furnish a backing for the upper throughout the greater part of its area and so constructed and arranged as to leave a space above the level of said reinforcing member where the top margins of the upper and lining member may be secured together with no portion of said reinforcing member interposed between them, whereby said marginal portion of the assembled upper may engage the foot yieldingly, said reinforcing member having a part cut away for a substantial distance at the throat portion of the upper to leave a space where a portion of both upper and lining may freely expand and contract, and an elastic member disposed across said space and secured to the upper to increase the elastic effect of the assembled upper while at the same time reinforcing the upper at the cut-away part of the reinforcing member.
- 20 6. In a shoe, an elastic fabric upper, an elastic tape member secured to the upper margin of the upper, an elastic fabric lining member united to the upper along their top edges, said upper and lining member being cut on the bias to allow for stretch both lengthwise and crosswise of the shoe where it is not reinforced, a reinforcing member of non-elastic material interposed between the upper and the lining members and secured with the said members to the shoe bottom to provide a backing for all parts of the upper which would tend to become distorted due to pressure of the wearer's foot and constructed to leave a space at the top margins of the upper and lining for the elastic tape member, said tape member being interposed between the upper and the lining and serving to augment the elastic effect of the assembled upper around the top edge portions of the latter whereby the foot is yieldingly engaged, said reinforcing member having a part cut away to leave a space at the throat portion of the upper wherein both upper and lining member are free to expand and contract, and an elastic member disposed across said space and secured to the upper to increase the elastic effect thereof while at the same time reinforcing the upper at the cut-away part of the reinforcing member.
- 25 7. In a shoe, an upper member and a lining

- member both of elastic fabric, cut on the bias to allow stretching both lengthwise and crosswise of the shoe at the throat thereof, a line of stitches securing the upper and lining members together near their top edges, a second line of stitches passing through the top margins of the upper and through a part of the lining which had been folded over the top edges of the upper and lining members following the insertion of the first line of stitches, both lines of stitches comprising elastic thread so arranged as to yield during stretching of the top marginal portions of the lining and upper, whereby there is provided an

edge of pleasing appearance which is also sufficiently elastic to retain the shoe comfortably on the foot, and a reinforcing member interposed between said upper and lining members and secured with said members to the shoe bottom, said reinforcing member being substantially coextensive with said upper and lining members below said second line of stitches but having a part cut away below the throat to permit expansion and contraction of adjacent parts of the upper and lining members.

CHARLES E. EDWARDS.
